ELECTRIC FORGING AND APPARATUS
THEREFOREmeric Gaspar, London, England, assignor to
Omes Limited, London, England, a British
companyApplication June 30, 1939, Serial No. 282,244
In Great Britain April 27, 1938

4 Claims. (Cl. 219—3)

This application corresponds to the application of Gaspar and Omes Limited, Serial No. 12,637/1938 which was filed in Great Britain on April 27, 1938.

5 This invention comprises improvements in or relating to electric forging and apparatus therefor. It has previously been proposed to forge rods to a point by electrically heating while under tension so that as soon as the material becomes 10 softened it is drawn out until it breaks.

It has been found, however, that in some cases in tension forging the structure of the steel 15 may be damaged by overheating and burning, and also that the points produced are not always identical in shape with one another. For some purposes, such for example as the manufacture of projectiles, the points produced are too rounded and with some steels the points may break off flat after reduction of the section has 20 proceeded to a certain degree. Again, steel should not be deformed unless it is hot enough, otherwise the structure of the metal will be damaged. With the previously existing apparatus however in which the tension was applied at 25 the same time as the initiation of the heating current, or otherwise controlled solely at the will of the operator, it was probable that deformation would be started before the proper forging temperature was reached. It is an object of the 30 present invention to improve the process in these respects.

According to the present invention a process of electric forging under tension is characterised by the fact that the tension is applied only after the piece to be forged has reached a predetermined forging heat and that the heating current is cut off, or at least reduced, prior to the application of the deformation under tension. It is found that in this way the forging operation can be caused to take place within the limits of forging temperature of the steel under treatment and satisfactory tapered shapes can be produced, including particularly shapes corresponding to the pointed ends of projectiles.

45 The application of tension to a workpiece may be initiated automatically by a heat-responsive element in the neighbourhood of or in contact with the heated portion of the workpiece. Again, the reduction or cutting-off of the heating current may be controlled, so as to occur automatically, 50 by a heat-sensitive device in the neighbourhood of or in contact with the heated portion of the workpiece.

The invention further comprises an electric forging apparatus comprising in combination two

work-holding vices for gripping the workpiece at separated points along its length, means for supplying electric current to the workpiece through the work-holding vices to heat it, means for moving the vices apart so as to apply tension to the workpiece and a device for simultaneously cutting off or reducing the heating current and initiating the operation of the means for moving the vices apart.

The heat-responsive element above referred to may consist of an "electric eye" which is electrically connected to a relay, operation of which cuts off or reduces the heating current and initiates the forging movement. The tension for forging may be applied by means of an hydraulic ram operatively connected to one of the vices and under the control of an hydraulic valve which is magnet-actuated, the magnet being controlled by the heat-responsive element.

In some instances instead of, or in addition to applying tension to the workpieces the forging of the point can be effected by swaging tools which are applied at a time (corresponding to that of the application of the tension to the workpiece above described) after the workpiece 25 has been brought to the desired heat and the forging operation is (as before) so conducted that the current is diminished or cut off before the reduction of the cross-section of the workpiece has proceeded too far.

30 The following is a description by way of example of one form of apparatus in accordance with the invention and of the process of the invention as carried out therein.

In the accompanying drawings—

35 Figure 1 is a side elevation and Figure 2 a plan of a forging machine;

Figure 3 is a diagrammatic representation of the working parts and of the electrical and hydraulic connections;

40 Figure 4 is a diagrammatic plan of an alternative construction;

Figure 5 shows the pointed structure produced,

Figure 6 is a vertical sectional view taken substantially on the line 6—6 of Figure 4.

45 Referring to Figures 1 and 2 the forging machine comprises a bed plate 11 having longitudinal guideways 12 supported on a framework 13 within which are located, behind louvred cover plates 14, the electrical step-down transformer 50 for supplying heating current and an electrically driven pump for hydraulic power. These latter parts are not illustrated in detail as they are common practice in forging machines.

Upon the longitudinal guideways 11 there are 55

mounted two work-holding vices 16, 17 which are capable of movement along the guideways. The vice 17 is insulated from the lathe bed and the two vices are connected to the terminals of the step-down transformer above referred to so that when a workpiece 18 is gripped so that it extends between the vices, the portion of the workpiece which spans the interval between them becomes heated to forging temperature.

10 Each of the vices comprises a body portion which supports a lower vice jaw 19 and an hydraulic cylinder 28 containing a ram 26 which is connected to an upper movable vice jaw 22. The vice jaws 19, 22 are made removable from the portions of the vice which hold them and they are interchangeable with other vice jaws, the various vice jaws being shaped, where they meet together, so as to grip various desired shapes of workpieces. The jaw members 19, 22 are aligned with one another in a direction parallel with the guideways of the bed plate so that the workpiece 18, when gripped, is parallel with the guideways. The vices 16, 17 are made of bronze or some other good electrical conductor. The vice 17 is adjustably secured on the guideways by means of side rods 23 which are insulated from the vice and are connected to a crosshead 24 operated by a screw 25. The screw 25 passes through a screwed nut 26 which is journaled in a transverse bracket 27 at the end of the machine bed. The nut 26 carries at one end worm-wheel teeth 28 which mesh with a worm 29 mounted on a shaft 30. The shaft 30 carries a sprocket 31 which is rotated by means of a chain 32 from a handwheel 33 and thus the vice 17 can be set, by rotation of the handwheel, at any desired position along the bed.

15 The other vice 16 is connected by rods 34 to a crosshead 35 which is made capable of sliding along the guideways 12 and is secured on the end of a ram 36 working in an hydraulic cylinder 37. The cylinder is bolted by flanges 38 to the bed plate 11. The hydraulic cylinder 37 is made double-acting so that it can force the vice 16 to move in either direction. The vices 16, 17 are given sufficient gripping force upon the workpiece to enable them to prevent the workpiece from sliding through the jaws under the tension required for forging. Any other additional means for gripping the ends of the workpieces and preventing them from sliding through the vice jaws may be provided if this is found desirable or necessary.

20 Between the vices and arranged in a position so that it points toward the central portion of the workpiece 18 where it spans the interval from vice to vice there is a photo-electric cell 40 which is sensitive to the rise of temperature brought about in the workpiece by the heating current. Such a photo-electric cell is sometimes known as an "electric eye." The cell 40 is so positioned and adjusted that upon the workpiece reaching the desired forging temperature it will actuate a relay 41 (Figure 3). The relay is energised by a supply circuit 42. The combination of "electric eye" and relay is well-known in itself and therefore the construction of these parts is not indicated in detail in the drawing. The relay 41, when actuated, serves to break a circuit 43, 44, 45 which normally supplies with current a magnet 46 of a clapper switch 47. The switch 47 controls the circuit of the primary winding 48 of the step-down transformer before referred to which is shown at 49 in Figure 3 and has a secondary winding 50. The circuit of the primary

winding 48 is energised from a power supply 51. When the relay 41 operates to break the circuit 43, 44, 45 the clapper switch magnet 46 is de-energised and the clapper switch opens, thus cutting off the supply of power to the transformer 49 and thereby cutting off the heating current from the workpiece 18.

25 The relay 41 at the same time energises a control solenoid 52 through the circuit 53, 54. The control solenoid 52 is connected by a rod 53 to a control lever 54 which projects from a valve box 55. This lever and the valve box can also be seen in the plan, Figure 2. The object of the energisation of the solenoid 52 is to cause the ram 36 to be retracted and apply tension 15 to the workpiece in order to draw it into a pointed shape between the vices 16, 17. For this purpose the valve box 55 is supplied with oil under pressure from a pump 56 through a supply pipe 57. It is not necessary to describe in detail the construction of the valves but is sufficient for the present purpose to explain that on depression of the lever 54, either by hand or by the action of the solenoid 52, the oil pressure is directed into the pipe 58 which leads through a throttle valve 59 to the front end of the hydraulic cylinder 37. At the same time the pipe 60, which is in communication with the back end of the cylinder through a throttle valve 61, is connected by the action of the lever 54 in the valve box 30 55 with an exhaust pipe 62 leading to an oil return sump 63 from which the pump 56 draws its supply of oil. On the other hand, if the lever 54 is raised, the pipe 58 is connected to the exhaust pipe 62 and the pipe 60 to the oil pressure supply, thereby reversing the movement of the ram 36 and causing it to advance. The lever 54 is urged upwardly by a spring 64 and the latch 65 is capable of holding it down. The latch 65 is connected to a sliding rod 66 mounted at the 40 side of the machine bed 11 so as to extend parallel to the ram 36. The rod 66 is urged by a spring 67 in such a direction as to cause the latch 65 to tend to slip over the lever 54 and hold it down as soon as it is depressed. Upon 45 the rod 66 is a collar 68 which can be set at any desired position and held by a screw. The collar 68 is in line with a striker 69 carried on the crosshead 35 and thus, when the ram 36 is caused to be retracted by depression of the 50 lever 54, the movement will proceed until the striker 69 engages the collar 68 and withdraws the latch 65. Thereupon (since the relay 41 will have been de-energised in the meantime by the fact that the workpiece has been severed 55 and that the "electric eye" 40 is no longer focussed upon a fully heated portion of the workpiece) the lever 54 will be forced upwardly by the spring 64 and the movement of the ram will be reversed so as to bring it forward into position 60 ready to operate upon a new workpiece. The throttle valves 59 and 61 serve to regulate the speed of movement of the ram, the one in the one direction and the other in the other and thus to determine the speed of the forging operation 65 and the time taken for the return movement, which latter should be sufficient to permit the operator to prepare for the insertion of another workpiece.

70 The extent of the movements of the ram in both directions is limited by stops. The adjustable rod 70 which is able to slide in a boss 71 on the top of the cylinder 37 constitutes a back stop to prevent undue retraction of the vice 16 and the two screwed rods 72 which pass through the 75

the crosshead 35 are provided with heads 73 to constitute a front stop. The heads 73 carry sprockets 74 which are connected by chains 75 and one of the sprockets has a handle 76. By 5 this means the two screws 72 can be simultaneously rotated to an equal extent and brought into any desired position of adjustment.

The vices 16, 17 are controlled from the valve box 55 by a lever 77 parallel to the lever 54. The 10 lever 77 operates the valves in the valve box 55 which serve to admit fluid under pressure to the pipe 78 leading to the upper end of the cylinders 28 when the lever is depressed, while at the same 15 time connecting the pipe 79, connected to the lower ends of the cylinders, to the exhaust pipe 82. Depression of the lever 77 will therefore 20 close the vices 16, 17 simultaneously upon the workpiece. On the other hand, when the lever is raised into the position indicated in Figure 3 25 the connections of the pipes 78 and 79 to pressure and exhaust respectively will be reversed and the vices will be opened to release the workpiece, or rather the portions of it which remain in the vices after the forging operation.

25 The pressure which is applied for holding the workpiece and for the forging operation can be regulated by means of a by-pass relief valve 80 on the delivery side of the pump 56. The relief valve has a screwed stem 81 screwing down of 30 which modifies the pressure of the relief valve spring and thus determines the hydraulic pressure at which the system operates.

On a branch 82 from the pipe 78 there is connected a switch control cylinder 83. This 35 contains a piston and a return spring 84 and serves to operate a piston rod 85 in such a way that the presence of hydraulic pressure will cause the rod 85 to be pressed forward out of the cylinder into the position shown in the drawings. The rod 85 is connected to two switch arms 86, 87 of a 40 double-pole switch in the supply circuit to the transformer winding 48. Failure of the hydraulic pressure will therefore lead immediately to the current being cut off but as long as the pressure is maintained in the pipe 78 and the vices 45 are therefore closed, the transformer will be energized, subject of course to the control of the clapper switch 47 already described.

In addition to the controls already described 50 there is a push button 90 which normally closes the circuit leading from the relay through the wires 43, 44, but which, when pushed, breaks this circuit and makes another through the wires 91, 92 which by-passes the relay 41 and energizes the solenoid 52 as an alternative to the energisation 55 of this solenoid by the relay. Consequently the operator, if he desires, can cut out of operation the "electric eye" 40 and cause the transformer 49 to be de-energised by operating the push button 90, at the same time applying the tension forging force to the workpiece through the action of the solenoid 52. In this case the control 60 of the operations is effected by hand instead of automatically by the "electric eye."

65 In the operation of the apparatus therefore the operator begins with the levers 54, 77 in their uppermost position as indicated in Figure 3. The vice jaws 19, 22 of both vices will then be open and the ram 36 will be advanced to its full extent. After placing a workpiece 18 in position, the operator depresses the lever 77, thus closing 70 the vices and actuating the hydraulic switch 87 to close the transformer circuit. As soon as the work reaches forging temperature the "electric eye" 40 operates the relay 41 and breaks the

transformer circuit by de-energising the clapper switch magnet 46. At the same time the relay 41 energises the solenoid 52 and draws down the lever 54, thereby setting the ram 36 in movement to draw the vice 16 away from the vice 17 and cause the work to be drawn out. With the normal setting of the parts, this movement will continue until the workpiece is drawn out to two pointed pieces somewhat similar to the illustration in Figure 5, although the degree of 10 taper of the point depends not only upon the temperature of the workpiece but also upon the distance apart of the vices before the operation is commenced and the speed of the drawing operation, which latter can be regulated by means 15 of the throttle valves 59, 61. If it is desired merely to forge a thinner place in the workpiece, and not completely to sever it, the stop 10 is adjusted to terminate the motion before the workpiece has been fully severed. Immediately 20 before the end of the movement of retraction of the ram 36 the striker 69 is made to engage the collar 68 and withdraw the latch 65, thereby permitting the lever 54 to rise and causing the ram 36 to stop and to begin a forward 25 movement. The operator raises the lever 77, thus opening the vices 16, 17 and removes the workpiece. If the throttle valve 61 is suitably adjusted he will have time to insert another workpiece before the ram 36 completes its forward movement, upon the termination of which he will lower the lever 77 again and thereby close the vices upon the workpiece. Thereafter the recommencement of the drawing operation depends upon the workpiece acquiring the appropriate temperature which is observed by the "electric eye" 40, or alternatively by the operator.

It should be observed that if desired the screw 25, which serves to adjust the vice 17, may be 40 made hollow so that a long length of bar can be fed into the vice jaws through the screw, and in that case a series of workpieces could be severed one after another by feeding in a fresh piece of bar between the vices after each severing operation.

Instead of producing pointed ends on a workpiece by drawing the vices apart, the operation 45 can be conducted if desired as shown in Figure 4. In this case 50 represents the secondary winding 50 of the transformer which is connected to two vices 116, 117. The vices have clamping jaws 118 which may be similar to the jaws 19 and 22 of Figures 1 to 3. Between these clamping jaws a workpiece 118 may be held and heated as already 55 described. In addition to the clamping jaws the vices have supporting ball bearings 120 which surround the workpiece and are able to support it for rotation even after the vice jaws 119 have been released. Between the vices 116, 60 117 there are mounted two cradles 121, 122 which are pivoted below the workpiece and extend upwardly one at the front and one at the rear as 65 illustrated in Figure 4 and carry at their upper ends on each side of the workpiece rotatable 70 swaging rollers 123. The swaging rollers are mounted on spindles the axes of which are parallel to the axis of the workpiece 118 and the spindles 124 carry at their ends sprockets 125. The sprockets are driven by chains 126 from a larger sprocket coaxial with the pivot of the cradles 121, 122. The cradles are capable of 75 being rocked so as to advance the swaging rollers 123 into contact with the workpiece 118 by means of a right- and left-hand screw 127 which 78

passes through the cradles below the rollers 123 and carries on the front of the machine a hand-wheel 128.

An "electric eye" is provided above the workpiece similar to the "electric eye" 48 of Figures 1 to 3. In the operation of the device the workpiece is first heated by applying the current after the vices 116, 117 have been closed together upon the workpiece. As soon as the work becomes hot enough for forging, the "electric eye" operates a relay similar to the relay 41 and the vices are so connected that the vice jaws 119 are released from the workpiece, thus freeing it for rotation. At the same time the rollers 123 are set in motion and the operator, as soon as he sees these events happen, actuates the hand-wheel 128 to close the swaging rollers 123 upon the workpiece. The swaging rollers, since they are being rotated and the workpiece is rotatably mounted in the bearings 126, will cause the workpiece to rotate while they are being forced inwardly into it and as a result the workpiece is swaged to a shape similar to that shown in Figure 5 and the two halves are separated from one another. Therefore after the swaging rollers are withdrawn and the workpiece is taken out of the electrodes 116, 117. It will be understood that with this arrangement the vice jaws do not move along the bed on which they are mounted and, except for some means of longitudinal adjustment, no necessity exists for such longitudinal movement. The cylinder 31 and ram 36 would therefore be omitted from such a construction.

While a particular shape of swaging roller has been illustrated which is adapted to produce points like the end of a projectile, it will be understood that any other shape of swaging roller could be adopted if desired. The action of the rollers can be assisted if desired, by applying tension, providing the vice 116 is made longitudinally movable. Tension applying means similar to that hereinbefore described may be employed for this purpose.

I claim:

1. An electric forging apparatus comprising in combination two work-holding vices for gripping a workpiece at separated points along its length, means for supplying electric current to the work-

piece through the work-holding vices to heat the workpiece, means for moving the vices apart so as to apply tension to the workpiece, a device reducing the heating current and initiating the operation of the means for moving the vices apart, and automatic means responsive to a predetermined increase in temperature of said workpiece to actuate said device.

2. In an electric forging apparatus, the combination with means operable to grip a workpiece, of means for supplying electric current to the workpiece through said gripping means to heat the workpiece, means for applying force to the workpiece to deform and reduce the section thereof, and means responsive to a predetermined increase in temperature of said workpiece for simultaneously reducing the supply of electric current thereto and initiating operation of said force applying means thereon.

3. Electric forging apparatus comprising in combination two work-holding vices for gripping a workpiece at separated points along its length, means for supplying electric current through the work-holding vices to the workpiece to heat the latter, means for rotating the workpiece about its own axis, swaging rollers mounted so as to be applied to the workpiece to reduce the section thereof, and means responsive to a predetermined increase in temperature of the workpiece for reducing the heating current, for applying the swaging rollers to the workpiece, and for initiating operation of said workpiece rotating means.

4. In an electric forging apparatus, the combination with means operable to grip a workpiece, of means for supplying electric current to the workpiece through said gripping means to heat the workpiece, means for applying force to the workpiece to deform and reduce the section thereof, electrical means for simultaneously initiating operation of said force applying means and reducing said heating current, means including a thermal device responsive to rise in temperature of said workpiece for energizing said electrical means, and manually controlled means for energizing said electrical means independently of the operation of said thermal device.

EMERIC GASPAR.
